(57) **CLAIM**

The ornamental design for a hose stand with decorative shelf, as shown and described.

DESCRIPTION

FIG. 1 is a right side perspective view of a hose stand with decorative shelf;

FIG. 2 is a front view of the embodiment in FIG. 1;

FIG. 3 is a back view of the embodiment in FIG. 1;

FIG. 4 is a left side view of the embodiment in FIG. 1;

FIG. 5 is a right side view of the embodiment in FIG. 1; and

FIG. 6 is a top side view of the embodiment in FIG. 1.

The broken lines represent portions of the hose stand with decorative shelf that form no part of the claimed design.
